UNITED STATES PATENT OFFICE

MINARD A. POSSONS, OF CLEVELAND, OHIO, ASSIGNOR TO AMERICAN STOVE COMPANY,
OF ST. LOUIS, MISSOURI, A CORPORATION OF NEW JERSEY

GAS COCK FOR RANGES

Original application filed November 13, 1928, Serial No. 319,108. Divided and this application filed
October 30, 1929. Serial No. 403,544.

This invention relates to improvements in
gas cocks for ranges and it is especially con-
structed to be used in connection with what
has become known in the art as ranges hav-
ing concealed manifolds.

For a great many years gas ranges have
been manufactured in which the gas mani-
fold is located outside of the burner frame
of the range. This improvement is a particu-
lar construction of a gas cock that adapts it
10 for use when located within the burner range
housing and having the handle of the cock
located outside of the range housing for op-
eration.

15 The construction here shown was original-
ly filed in application Serial No. 319,108 of
the present applicant for improvements in
burners and cocks therefor, said application
having been filed November 13, 1928 and
20 this application is a division of the above
mentioned application.

The improvement made the subject matter
of this application pertains to the provision
25 of a combined cap and nipple that closes the
outlet of the housing; the cap and nipple
being in a line with the valve and its handle
for operation, and it also pertains to a special
construction of the valve whereby it contains
30 a spring which is located between the valve
and the said nipple for normally holding the
valve gas tight in its tapered seat.

Other features of the invention will be
understood from the following description.

In the drawings:

35 Figure 1 is a sectional view of part of the
gas range housing and the said valve there-
in that communicates with a burner.

Fig. 2 is an enlarged longitudinal sectional
view of the improved valve with its closing
40 cap and its housing.

Fig. 3 is a cross sectional view on the line
3—3 of Figure 2.

Fig. 4 is a detached perspective view show-
ing the valve housing, the handle for oper-
45 ating the valve and the combined cap and
gas nipple closing one end of the valve hous-
ing.

Fig. 5 is a perspective view of the valve
housing and the valve, the two parts being
50 shown in separated relation.

Referring now to the drawings in which
A indicates the burner top of a range, the
front portion of the burner top being closed
by a front panel C which panel serves to form
a member for concealing the manifold G
55 which is embraced within the burner top
A and within the concealing plate C. The
gas cock housing F is also enclosed within
the burner top construction and at E in any
desired form of burner with which the gas
60 conveying tube H communicates.

Having thus designated in general terms
the parts which go into the make up of the
present invention, the improved gas cock will
now be more specifically described.

In the form here shown the burner E may
be an integral cast construction having the
gas induction tube H projecting from its
front edge. In the instance here shown the
outer end of the induction tube H is en-
70 larged to form a bell-like portion 10 which
carries the usual shutter 12 that is common
and well known in connection with gas burn-
ers. The inner end of the induction tube
H communicates with the hollow burner
75 which may be of any desired construction so
far as the present improvement is concerned.

In the present construction the induction
tube H of the burner E is quite short and
means are provided for elongating the pas-
80 sage of the gas and air before it reaches the
burner openings and one of these means is
described in the application of which this is
a division.

The valve construction here shown has its
85 housing F comprising a central portion 22
in which is mounted for oscillation the valve
member or plug 23. One side of this housing
is provided with a threaded nipple 24 which
extends at right angles to the part 22 and
preferably upwardly and enters the manifold
G located thereabove. The outer end 25 of
the valve extends through the manifold and
valve housing concealing plate C sufficiently
90 to receive an operating handle 26 that is se-
cured thereto by means of a screw member 30.

The outer end of the valve housing is pro-
vided with a projection 31 and the inner
face of the handle hub is provided with pro-
jections 32, the said projections cooperating
100

to limit the rotary movement of the valve and thereby of the gas cock.

Attention is directed to the special construction of this valve in that the valve plug 23 thereof has a centrally arranged longitudinally extending chamber 33 which communicates with the inlet nipple 24 of the valve housing through a laterally extending opening 34 formed in the said valve plug. It will be noted that the outer end of this chamber 35 is closed and that the inner end of the valve plug has an enlarged chamber 36 which receives a spiral spring 37 mounted within the said chamber. The inner end of the valve housing 22 is externally screw threaded as at 39 and adapted to receive the internally screw threaded flange 16 of the nipple 38. This nipple is externally screw threaded as at 51 and is adapted to receive an internally screw threaded member 50 to serve as means for adjusting the flow of gas through the said nipple. This special construction however has nothing to do with the present invention as it may be varied without affecting the present improvement.

It will be observed that the enlarged chamber 36 that receives the spring 37 is made larger than the opening 49 formed in the nipple 38 so that the coil spring 37 has its inner end resting against the outer end of the nipple and has its outer end resting against the inner end of the said chamber 36.

Attention is particularly called to the fact that the valve plug 23 has its handle and outer end smaller than its inner end and that the housing 22 is correspondingly constructed to receive the said valve plug. Therefore the arrangement of this spring between the inner end of the valve and the outer end of the nipple serves to cause the valve plug to be seated in its housing.

In Figure 3 is shown that the wall of the spring receiving chamber 36 is provided with longitudinal grooves 55 and is therefore adapted to receive a tool suitably constructed for rotating the same. This rotation of the valve plug is necessary in grinding the valve plug in position in its housing 22 thus making a ground joint between the two members and thus establishing a gas tight seating of the plug in the housing.

Attention is also called to the fact that the valve plug is very much shorter than the ordinary gas valve plug and that the taper thereof is much more abrupt. This construction however while it is very advantageous in the construction of the valve, forms no part of the present invention except that it affords room for the spring 37 and thus enables the spring to efficiently hold the valve to its seat.

I wish it understood that the particular construction described herein may be varied without departing from the invention described so long as the variations come within 65 a fair interpretation of the appended claims.

Having thus described my invention what I claim and desire to secure by Letters Patent is:

1. A valve of the oscillating type, comprising a housing, a valve plug in said housing, an inlet at the side of the housing and at the side of the plug, a longitudinal opening in the plug for the passage outward of gas therethrough, a cap comprising a nipple closing the outlet end of the housing and means to oscillate said plug for opening and closing the valve.

2. A gas valve of the oscillating type comprising a housing having a tapered opening therein, a tapered valve plug in said opening, a gas inlet at the side of the housing adapted for communication with a longitudinal opening in the plug, one end of the longitudinal opening of the plug being closed and the other end of the opening communicating with a combined cap and nipple, a coil spring mounted in the plug and engaging the cap for exerting an outward pressure upon the plug for keeping it tight in the tapered housing opening, and means to oscillate said plug for opening and closing the valve.

3. An improved gas valve comprising a housing having therein a tapered opening, a tapered valve plug mounted for oscillation in said opening, one end of the housing opening being closed by the plug and the other end of the opening being closed by a combined jet and cap, and a gas inlet opening at the side of the housing, the plug being provided with a longitudinal passageway communicating at one end with the nipple, a port in the side of the plug adapted for communication with the inlet opening of the valve housing, a coil spring mounted within the longitudinal passageway of the plug and engaging the cap, said spring exerting a pressure to hold the plug tightly within the tapered opening of the housing, and means to oscillate said plug for opening and closing communication between the longitudinal passageway of the plug and the inlet opening of the housing.

In testimony whereof I hereunto affix my signature.

MINARD A. POSSONS.
